EXPLOSIVE PACKAGE

Dale S. Partridge, Overland Park, Kans., assignor to Gulf Oil Corporation, Pittsburgh, Pa., a corporation of Pennsylvania

Filed Apr. 13, 1966, Ser. No. 542,250
5 Claims. (Cl. 102—24)

ABSTRACT OF THE DISCLOSURE

A combination of both shattering and heaving effect, as well as more efficient utilization of explosive force is obtained from a substantially cylindrical package of ammonium nitrate-based aqueous slurry explosive which surrounds a charge of dry ammonium nitrate-carbonaceous fuel explosive sealed within a water-impervious barrier.

This invention relates to packaged blasting explosives. More particularly, this invention is directed to an explosive package in which a water-sensitive explosive is contained in a sealed impervious container inside a mass of water-insensitive explosive.

Blasting explosives comprising ammonium nitrate and a carbonaceous fuel with or without sensitizers and auxiliary explosive additives are now very well known and widely used. The conventional ammonium nitrate-fuel oil explosive compositions have very desirable properties, particularly with regard to their ability to heave large masses of rock or earth. However, when blasting is done in vertical drill holes, it frequently happens that water enters and collects in the hole. Ammonium nitrate-fuel oil explosives are sensitive to the presence of water and when wet do not give their usual performance. Therefore, it is necessary that such explosives be kept dry. When these explosives are sealed in water-proof containers, the specific gravity of the container is usually less than that of water, and so it is difficult to make the explosive charge sink to the bottom of the hole. In coping with this situation, a new type of water-insensitive explosive composition of high specific gravity has been developed. This new class of explosives contains ammonium nitrate, a solid fuel, auxiliary oxidizers and sensitizers, water, and a water-dispersible colloid which stabilizes the mixture against settling of suspended solids. The new aqueous slurry explosives have become popular in hard rock mining where rather large vertical drill holes are employed and entrance of water into the holes occurs frequently. The high specific gravity, water-insensitivity, and brisance of the aqueous slurry explosives are very desirable. However, they are different in character from the ammonium nitrate-fuel oil explosives. The desirability of using the two types of explosives together so as to obtain the combined advantages of both has become apparent. For example, a practice which has been used to some extent is the loading of aqueous slurry explosives in a bottom of a drill hole along with a suitable booster and detonator and loading ammonium nitrate-fuel oil explosive on top of the slurry explosive; then firing the entire charge. The resulting explosion is somewhat unbalanced in its effects, however, as might be expected. It has been attempted to intersperse packages of ammonium nitrate-fuel oil explosive with aqueous slurry explosive in the drill hole, but this has been found to be inconvenient and to give nonuniform results. Among other things which may occur in the blasting of such a charge are the shifting of explosive packages after they are in the hole and accidental puncturing of ammonium nitrate-fuel oil packages during placement in the hole, permitting the explosive to become wet and less effective.

I have found that the desirable features of the two types of explosives may be obtained conveniently and cheaply and with uniform results by means of a novel

2

packaging arrangement. Preferably, my invention consists of a substantially cylindrical package, in which a dry ammonium nitrate-carbonaceous fuel explosive is sealed inside a water-proof barrier and is surrounded by a mass of aqueous slurry explosive. The mass of aqueous slurry explosive may be in semisolid gel form and, if so, can be handled in drums or other rigid containers. The gelled mass may be contained in plastic bags which are dumped out of the containers into the drill holes so that the containers may be re-used or, preferably, the gelled mass is put in durable cylindrical plastic containers both for shipping and placement in the drill hole. The package possesses substantial advantages among which are the following: The water-proof bag of ammonium nitrate-fuel oil explosive is protected from punctures and retained in a centrally located position by the flexible mass of aqueous gel which surrounds it. The specific gravity of the entire package is greater than water so that the package will readily sink to the bottom of the drill hole into which water has entered. The efficiency of the combination of explosives in the package is greatly increased. This is believed to result from efficient utilization of the high heat of detonation of the ammonium nitrate-fuel oil explosive as a result of completely surrounding this explosive with the aqueous gel. The high velocity of the detonation of the aqueous gel explosive also appears to compensate for the normally lower velocity of the ammonium nitrate-carbonaceous fuel explosive. The mechanism by which improved results are obtained is probably not fully understood. However, it has been demonstrated that packaging in the reverse arrangement with the gel on the inside does not give equivalent behavior. It is therefore concluded that the benefit results from surrounding the dry explosive with the gel and by separating the two explosives with a water-impervious barrier.

By reference to the drawing and the following illustrative example, the practice of the invention will be clear to a person possessing skill in the art. The drawing presents a cut-away view of a complete package (FIGURE 1) as well as a cross-section of the same (FIGURE 2).

Example I

A tube of extruded polyethylene film 5 inches in diameter was closed at one end, filled with 25 pounds of a mixture of ammonium nitrate with 6 weight percent fuel oil and the open end was sealed. (See No. 1 in FIGURES 1 and 2.) The ammonium nitrate employed in this explosive consisted of 50 percent whole prills and 50 percent crushed prills so as to increase the bulk density, yielding an explosive composition with a specific gravity of approximately 1.0. The filled, impervious package of ammonium nitrate-fuel oil explosive was placed inside an extruded polyethylene tube 7 inches in diameter and 25 pounds of aqueous slurry explosive in semisolid gel form was placed in the larger tube so that it completely surrounded the smaller package of dry ammonium nitrate-fuel oil explosive (No. 3 in FIGURES 1 and 2). The external tube was then sealed for convenience in handling.

The aqueous slurry composition contained 42 weight percent ammonium nitrate, 14 weight percent sodium nitrate, 4 weight percent hexamethylenetetramine, about 15 weight percent coarse granular aluminum, about 1 weight percent paint grade aluminum flake, 23 weight percent water and about 0.6 weight percent guar gum.

The explosive package was lowered into an 8-inch diameter hole drilled vertically into Mesabi range taconite and was fired by means of an electric cap and a 1-pound pentolite booster placed in the bottom of the hole. The resulting explosion produced both the shattering of rock customarily observed with slurry explosive alone and at the same time also heaved the mass of rock away from the face of the deposit, indicating that it pos-

possessed the gas-producing and heaving ability characteristic of the dry ammonium nitrate-fuel oil explosives.

The essential features of the improved explosive package are the protection of the dry ammonium nitrate-fuel explosive from water and the surrounding of this explosive with the aqueous gel explosive. This may be accomplished in several ways. For example, individual ammonium nitrate prills may be impregnated with a hydrocarbon and coated to render them water-impervious, then mixed with the aqueous gel so that they become surrounded. Alternatively, small sealed plastic packages of ammonium nitrate explosives may be produced, either individually or attached together in a manner similar to link sausages, and fed into the package at the same time as the slurry explosive. Preferably a container is employed which is designed with a centrally located waterproof interior compartment which can be filled and sealed prior to placing the surrounding charge of aqueous slurry explosive.

The dry ammonium nitrate-fuel oil explosive should be substantially completely surrounded by the aqueous slurry. However, in a tall column of explosive, the dry ammonium nitrate explosive may be surrounded with aqueous slurry on the sides but not at one or both ends, with satisfactory results. In a charge of some length, however, with both ends covered only with the water-impervious barrier, less than a fraction of one percent of the total exterior surface remains not surrounded with aqueous gel. The surrounding of the charge is thus substantially complete, so that detonation of the dry explosive under the external pressure exerted by the high-velocity gel explosive is achieved.

In the above example, a charge consisting of half dry and half aqueous explosive apparently accomplished both of the jobs normally done by either of the two types of explosives in about the same size charge. This appears to indicate that some power is normally wasted in either the rock shattering by the aqueous slurry or the heaving of mass by the dry explosive, and that the combination in the package utilizes the total power of both explosives to better advantage. Although the 50-50 weight ratio of explosives in the package is not critical, approximately equal proportions are preferred for a product of general usefulness and versatility. In smaller drill holes of 5 to 7 inches in diameter a higher proportion of the dry explosive, for example as much as 65 percent, appears to be desirable. However, in larger holes of 9 inches or more in diameter, the proportion of dry explosive may be varied over a broad range, permitting the characteristics of the combination to be adjusted to compensate for variations in behavior which are attributable to the size of the charge, and to adjust heaving ability so as to place the dislodged rock at the desired distance from the face of the deposit.

The effect obtained by the explosive package of this invention is essentially a pressure versus time curve of a type not previously observed in ammonium nitrate explosives. As has been stated above, this is believed to result from the detonation of a dry ammonium nitrate explosive while surrounded by a previously initiated high velocity explosion. The size of the internal package of dry ammonium nitrate explosive does not appear to be of critical importance, as indicated by the following example.

Example II

An explosive mixture was prepared by distributing 34 parts by weight of waterproof ammonium nitrate blasting prills made in accordance with U.S. Patent 3,148,095 in an aqueous slurry mixture containing 15 parts of water, about 34 parts of water-soluble ammonium nitrate, 2 parts of paint grade aluminum flake, 4 parts of hexamethylenetetramine, 10 parts of sodium nitrate and about 0.5 part guar gum. The explosive mixture was packaged in plastic sausage casings of various diameters and was tested. At a diameter of 3 inches one charge failed to detonate, indicating that for small diameters, the explosive should be formulated with greater sensitivity. At diameters larger than 3 inches, the characteristic behavior of the improved explosive package was obtained with no failures. These results indicate that the dry ammonium nitrate explosive may be employed in packages as small as individual prills, if desired. Higher sensitivity requirements are usually characteristic of small diameter charges of blasting explosives. By employing a more sensitive slurry explosive, containing larger proportions of such components as sensitizers, auxiliary oxidizing agents and suspended solid fuel, this problem is readily alleviated. Sensitive explosives of the slurry type are available as articles of commerce and suitable formulations have been published.

The use of waterproof blasting prills as the internal dry explosive yields a readily pumpable explosive mass, so that the packaging procedure may be carried out with greater ease and safety.

What is claimed is:

1. A substantially cylindrical package containing a dry explosive comprising ammonium nitrate and a carbonaceous fuel, a water-impervious barrier sealing said dry explosive and a mass of aqueous slurry explosive surrounding said dry explosive, said aqueous slurry explosive comprising water, ammonium nitrate and suspended solid fuel.
2. A package according to claim 1 in which the water-impervious barrier is a flexible plastic container.
3. A package according to claim 1 in which the water-impervious barrier is a coating applied to the exterior surfaces of individual ammonium nitrate prills.
4. A package according to claim 1 in which the diameter is less than 9 inches and more than 50 weight percent of the explosive therein is a dry explosive comprising ammonium nitrate and a carbonaceous fuel.
5. A package according to claim 1 in which the diameter is at least 9 inches and about 50 weight percent of the explosive therein is an aqueous slurry explosive comprising water, ammonium nitrate and suspended solid fuel.
